TABULATION CONTROL SYSTEM

Louis M. Potts, Evanston, Ill., assignor to Teletype Corporation, Chicago, Ill., a corporation of Delaware

Application April 6, 1944, Serial No. 529,753

24 Claims. (Cl. 178—27)

The present invention relates to a printing telegraph apparatus and more particularly to telegraph receiving apparatus with movable carriage mechanism having automatic tabulation control.

The principles of this invention are herewith presented in several embodiments and are concerned with the provision of rotary platen telegraph printing apparatus equipped with a plurality of individual strip feeding devices. The invention is featured as being applied to commercial printing telegraph machines of the type generally illustrated and described in U. S. Patent No. 1,904,164, in which a transversely movable carriage supports a printing type basket and in which the control or character selection is transmitted to a set of horizontal vanes which are permutably tilted about their longitudinal axes, and then through said vanes to a set of notched code bars carried by the type carriage. In accordance with each permutable disposition of these code bars, a single one of the type pallets is struck against the particular platen with which the carriage is brought into alignment. A series of such platens are arranged on a common horizontal axis, but each one is individually actuatable so that the strip of printing material passing around it may be advanced independently of the movement of any of the other strips of printing material.

Under the control of various prearranged tabulation signals the carriage is rapidly advanced from its left-hand or any intermediate position to a predetermined selected position by the operation of the conventional carriage moving mechanism. As each selective position of the carriage is attained, printing may thereafter be consummated in accordance with the conventional practice known in telegraph and other printing devices of this class, and at the conclusion of printing in relation to any one of the selected strips of material there may be effected a further selection rightwardly, or under certain proposed conditions of operation the carriage may be invariably restored to its zero or starting (beginning of line) position in readiness for movement to any of the several platens rightwardly of such zero position.

In accordance with the provisions of one of the embodiments herewith proposed, a plurality of individual printing platens are supported so as to be shiftable between upper and lower case printing positions. In this embodiment there is provided means whereby printing upon any one of the platens may be effected in either of the case positions and accordingly, the selection of

any one of the several strips of material may be effected by a code selection in either one of the shift positions. In this embodiment, moreover, provision is made whereby the selection of one of the strips of record material is effected from a predetermined starting position of the printing carriage and thereafter when the carriage is moved from this starting position, printing may be performed by the use of the same signals which are utilized for effecting tabulation or carriage shifting selection without thereafter causing a tabulation response.

The principal object of the present invention is to provide a multiple tape printing telegraph apparatus in which single tabulation signals are utilized in the advancement of a common printing carriage to each of a plurality of printing strips, where printing is thereafter performed transversely of the strips, and during which printing, said strips may be individually advanced in accordance with the conventional practice of line feed operation without similarly affecting the adjacent strips of printing material.

The further object of the present invention is to provide a movable carriage type of printing telegraph apparatus in which a tabulation control mechanism is utilized for moving a printing carriage to any of a plurality of parallel ribbon supporting platens which may be individually shifted to upper and lower case printing positions without similarly affecting the adjacent printing platens.

In attaining the foregoing and other objects of the present invention there is utilized in various embodiments illustrated in the accompanying drawings the features of a horizontally disposed printing platen composed of a plurality of individual cylinders pivoted on individual shafts arranged on a common axis and each individually fed from a supply roll of strip material supported in an appropriate trough. Each of the printing strips is advanced by a spring loaded take-up roll and the movement is regulated by an escapement or tape feed device which is effective only when the printing carriage addresses the particular one of the several platens. Printing is performed transversely of the strip just as in the case of page printing telegraph apparatus and following each line of printing a conventional line feed operation is performed by the mechanism of the printing telegraph device customarily provided for this purpose.

Tabulation is regulated along a horizontal trackway by means of five code bars having on their uppermost edges various distributions of

V-tooth notchings. A series of probing levers pivotally supported and having probing terminals arranged in transverse alignment are pivotally carried by the transfer bell cranks which communicate the code setting from the transverse vanes to the type basket segments. When the type basket carriage is released from its leftmost or zero position and permitted to move rightwardly in search of the selected tape, the several probing levers ride in and out of the notchings on related code bars but upon attaining the selected position the notchings thereat are so arranged that all of the levers will then and then only be disposed in downward position permitting a transverse bail member to descend and instantly to effect the arrestment of further travel on the part of the carriage. In accordance with one of the embodiments herein taught, the selection of a second tape disposed to the right of any particular selected tape may be effected directly from the previous arrestment position; however, in accordance with the alternative plan of operation tabulation may be selected only from a zero position requiring, therefore, that following each printing upon a tape restoration of the carriage be obtained in order that the following tabulation selection will be enabled through the proper placement of the printing carriage.

In a modified embodiment of the invention there is featured an arrangement whereby each one of the printing platens is individually pivoted and is separately displaceable so that it may be shifted between two case positions under the supervision of the conventional key shift control apparatus provided in the standard mechanism. In this arrangement there is provided an escapement ratchet and pawl mechanism for advancing the tape in either one of its case positions through the agency of a common line feed control apparatus selected by the conventional line feed signal. In this embodiment a spring tensioned take-up roll is used as the medium for advancing the tape when movement thereof is permitted by the escapement device.

In accordance with the present invention a single printing mechanism and a single set of type elements is provided for recording on a plurality of separate pieces of record material which are arranged vertically instead of horizontally and in which printing is effected transversely of the strips and not lengthwise, thus the plurality of strips are in effect narrow pages, on each of which a separate and independent record may be made; for example, weather reports from different localities or cities, and similar information.

For a better understanding of the invention reference will now be had to the accompanying drawings and to the detailed specification following hereinafter, wherein like reference characters designate corresponding parts throughout, and wherein:

Fig. 1 is a front elevational view of a printing device such as is featured in U. S. Patent No. 1,904,164, modified by the addition thereto of an alignment of separate platens and vertical ribbon supporting mechanisms together with the tabulation control apparatus incident to the present invention;

Fig. 2 is a side elevational view, partially in section, of the apparatus featured in Fig. 1;

Figs. 3 to 6 are transverse sectional views through the tabulation and selecting mechanism featuring various conditions of operation incident to the supervision of the mechanism for ob-

taining tabulation control and rapid carriage movement;

Fig. 7 is a simplified wiring diagram designating the electrical control circuit utilized in connection with the foregoing described embodiment of the present invention;

Fig. 8 is an enlarged detail view of a portion of the apparatus illustrated in Fig. 1 featuring the tabulation control mechanism;

Fig. 9 is a side elevational view partially in section viewed in the same field as Fig. 2 but featuring a modified adaptation of the present invention;

Fig. 10 is a fragmentary detail view of an individual shiftable printing platen which characterizes the modified form of the invention illustrated in Fig. 9; and

Fig. 11 is an enlarged detail section of the shiftable printing carriage and platen mechanism showing a changed position in dotted outline and viewed as in Fig. 9.

Since the features of the present invention are superimposed upon a well known fundamental printing telegraph structure, the general operation of carriage printing mechanism of this class will be but cursorily reviewed in connection with the following detailed description, reference being had to the above U. S. patent for information pertaining to the details of operation of the known structure. The description being given here pertains to those parts of the original structure only which relate to the present improvement.

The reference character 11 denotes a supporting base casting of general rectilinear formation having side walls and front wall portions extensively cut away to accommodate various items of movable apparatus and giving support principally to the manual controlled keyboard 12, featured in Fig. 1, through which the transmitting apparatus, indicated generally at 10, as well as local printing may be supervised; to several supporting track members which will be more particularly identified during the course of the ensuing description, and to the platen supporting apparatus preferably modified by the addition of upstanding side wall sections 13 for giving support to the take-up reel 14, Fig. 2, as well as to the individual tape feed mechanisms generally designated 15.

At the remote end of a motor driven shaft 16, Fig. 2, there is located a telegraph selecting mechanism which distributes incoming line signals after the manner explained in the above-mentioned patent and through the medium of various transfer devices the motion is ultimately imparted to a series of six horizontal selector vanes 17. The six vanes 17 represent a six-unit code combination signal, the sixth unit or impulse of which controls case shift, and the vane relating to the latter is specially designated 17a in Figs. 1 to 6.

In accordance with the various manners in which the vanes 17 may be disposed the resulting combination may afford a setting to set one of a plurality of function levers, the general class of which are designated 18, Fig. 2, but one of said function levers designated 19, differs from the general class by reason of its having no notched upstanding section, as in the general class 18, to be encountered by selected ones of the five code combination vanes 17. The sole selection characteristic of member 19 resides in a small section thereof disposed in front of vane 17a so that when the latter member is in its marking position, member 19 is selectable and may move leftwardly

about its pivot 21, but when said vane 17a is in its spacing position then member 19 is prevented from being selected.

In accordance with conventional practice a disposition of the sixth vane 17a is a distinguishing feature between the upper case and lower case condition of the apparatus so that as a result of the selection determining the position of vane 17a a signal is classified in terms of figures or letters shift. It will be understood, therefore, that in accordance with the arrangement now being described the selection of member 19 may be obtained in response to any "Letters" or unshift code combination regardless of the manner in which the general class of vanes 17 happen to be disposed, while such member 19 will invariably be barred from selection in response to any of the "Figures" or shift code combination signals also regardless of the disposition of the general class of vanes 17. There will now be described an arrangement whereby in response to the selection of member 19 there is effected a rapid shifting of the printing carriage 22 following which printing in the "Figures" shift position is obtained by disposing the vane 17a in its clockwise position whereat it will bar the further selective operation of member 19. The permutative disposition of the five code combination vanes 17 is mechanically transmitted through the medium of a set of five bell crank levers 23 each pivoted on an individual pivot screw 24 to a set of arcuate segments or code bars 25 the uppermost edges of which are variously notched so that when set in response to received signals, each setting affords an individual clearance to one of a series of type pallets 26. The manner in which this control is consummated is clearly explained in the referred to patent.

In accordance with the present improvement the vertically disposed arms of the bell cranks 23 are designed each to afford a pivot support, as at 27, to a horizontal probing lever 28. The probing extremities 29 of the several levers 28 are in substantially transverse alignment, see Figs. 1 and 8, though their several pivots 27 are located at various distances therefrom in accordance with the location of their respective bell crank arms 23. It is to be noted that as the vanes 17 may be variously disposed so also may the bell crank levers 23 be disposed with respect to the angular position on their respective pivots 24. For the purpose of fulfilling the requirements of the present invention, there being designated ten vertically disposed webs 31 (Fig. 1) of ribbon material upon which printing is to be effected, it will follow that the printing carriage 22 is to be selectively arrestable in any of ten different positions along its route of travel.

Accordingly, there are provided a set of selector bars 32, Figs. 1, 2, and 8, having transverse notchings 33, throughout the several of said bars 32 so located that upon predetermined dispositions of the bell cranks 23 the probing extremities 29 will be collectively receivable in correspondence with the notchings of the bars 32 relating to each one of the strips 31 when the carriage 22 moves into alignment with the first columnar printing position with respect to said strip. There being ten such strips 31, the code groupings 33 will necessarily be required to accommodate at least nine selectable positions, it being unnecessary to select the starting position assuming the condition happens to coincide with the first strip alignment.

When the several levers 28 moving leftwardly, together with the carriage 22 and the several bell cranks 23, ride in and out of the notchings 33 one or more of them may at various times drop into an associated notch 33 but so long as all of the levers 28 do not do so the transverse bail 34, Fig. 8, will remain in the position designated and the progress of the carriage 22 will not be arrested. However, upon the contingency of all of the levers 28 finding an alignment of notches 33 into which their probing extremities 29 may descend at the same time, the bail 34 will in response to spring 35 (Fig. 1) rock counterclockwise about pivot 36 thrusting the plunger 37 downwardly (see also Figs. 3 to 6, inclusive) to strike with its lowermost extremity 38 the horizontal bar 39 which extends the full width of travel of the carriage 22, as best designated in Fig. 1.

The aforescribed transmission of movement on the part of bail 34 through plunger 37 to the bar 39 is instantaneous, and bar 39 in turn being part of a bail lever 41 (Fig. 3) likewise imparts instantaneously this motion to a pair of pivotally supported pawls 42 and 43. As best indicated in Figs. 3 to 6, bail lever 41 is pivoted on opposite trunnion pins 44 in a stationary part of the framework and an extremity 45 of said bail extends so as to engage both of the tail portions of pawl levers 42 and 43 which together engage, with their shouldered extending portions, notches in a horizontally movable trip bar 46. Pawl 42 is pivoted at 47 in the aforescribed selectable member 19 while pawl 43 is pivoted as at 48 in a stationary part of the supporting structure so that when the stepping pawl 42 is reciprocated, there may be imparted a step-by-step movement to the bar 46 rightwardly because pawl 43 serves to maintain said bar in said position.

Actually, the motion imparted by a single step on the part of pawl 42 is sufficient to thrust the foremost portion of bar 46 against the insulation piece 49 (Figs. 3 to 6) of a contact blade forming part of the contact pair 51 for opening the transmitting circuit during the contingency of selection of member 19. In Fig. 7 is shown schematically a circuit arrangement for suppressing transmission during the time the type carriage is being moved into tabulating position from one column to another. In this figure, a receiving perforator-transmitter is indicated generally at 194. This may be a combined unit or it might be merely a receiving reperforator and a separate transmitter unit with the tape passing from the reperforator into the transmitter in well-known manner. The incoming signals are received by a selector magnet 195 which selectively controls the perforator portion of the combined unit 194. The prepared tape passes into the transmitter portion and controls the transmitting contacts 196. The signals from contacts 196 control the selecting magnet 197 of the apparatus according to the present invention. The contact 51 in the receiving printer apparatus with which the present invention is concerned, is in the circuit of the clutch control magnet 198 of the transmitter, and when contact 51 is opened during a tabulation operation, magnet 198 is de-energized and transmission is suspended or suppressed until the correct strip 31 has been selected and the type basket 22 is properly located for printing on said strip. In addition to this response, an upstanding portion 52 integral with bar 46 engages one arm of an acute angled bell 75 crank 53 pivoted at 54 whose other arm instantly

thrusts against a sidewardly projecting lug 55 integral with a pivoted lever 56 freely rotatable upon a transverse shaft 57.

The movement thus imparted to lever 56 overcomes the influence of its return spring 58 and results in the lifting of blocking projection 59 therefrom of the path of the stop shoulders 61 of a disc 62 carried by the shaft 16 with which are integrally associated the afore-described discs 62 as well as the driving gear 63, Fig. 2, which imparts rotation through driven gear 64 to the vertical shaft 65 for moving the type carriage 22 through the engagement of its driving gear 66 with the teeth of a transverse rack bar 67.

It will be noted, therefore, that as a result of the selection of member 19 and following its return movement clockwise about pivot 21, pawl 42 carried thereby will cause to be released shaft 16 together with its driving gear 63 for effecting the rapid movement of the type carriage 22. As the latter moves rightwardly, supported upon the cylindrical guide rod 68, (Fig. 2) and the transverse beam 69, the several probing levers 28 ride in and out of the various notchings 33 of the set of code bars 32. Meanwhile, it will be recalled that a particular code setting has been imparted to the selector vanes 17 establishing a predetermined displacement through the bell cranks 23 to the pivot 21 of said probing levers 28 so that their probing extremities 29 are predeterminedly arranged to agree with a particular transverse alignment of said notchings 33 located in said code bars 32, said notchings occurring at such a position that upon the encounter thereof with said probing extremities 29 the printing locus of the several type pallets 26 will then be in alignment with the starting position relative to one of the forms 31.

As a consequence, levers 28 (Fig. 8) will drop and permit the transverse bail member 34 to be rotated about its pivot 36. This will thrust control rod 37 (Fig. 2) downwardly under the influence of spring 35 and its lowermost extremity 38 will thereupon encounter the bail 39 imparting counterclockwise rotation thereto (as viewed in Fig. 2) about pivot 44. The remote end of bail lever 41 will accordingly be moved upwardly and projection 45 thereof will engage the tail of operating pawl 42 as well as latching pawl 43 removing the saw-tooth extremity thereof from the teeth of parallel motion trip bar 46.

Bar 46 thereupon may respond to the influence of the restoration spring 71 causing to be withdrawn the upstanding projection 52 which had been engaging and moving the acute angled bell crank 53. As a consequence, blocking lever 56 will be permitted to resume its illustrated position with lug 59 again in the path of one of the three blocking teeth 61 of disc 62.

When motion is withheld from the driving gear 63 it accordingly arrests carriage 22 since the driving train therebetween is continuous and depends upon the rotation of shaft 16 through which it is frictionally driven after the manner disclosed in the afore-mentioned patent.

Member 19 is actuated by a spring 72 to rotate in a counterclockwise direction about its pivot 21, during which motion the pawl 42 advances to engage a succeeding tooth in the notched lower edge of bar 46. However, the return movement of member 19 is imparted to it by a transverse bar 73 of the function lever bail 78 which similarly affects all of the general class of selectable function levers 18 discussed above.

Transverse rod 73 is thus effective upon the gen-

eral class of members 18 as well as upon special members 19 when it engages the inclined surface 74 of an upstanding arm 75 thereof, which arm is also provided with an abutment shoulder 76 (Figs. 3 to 6) that moves into the path of the print suppression element 77 secured to the function lever bail 78. In this way the printing bail assembly 79 is withheld from approaching its counterclockwise extreme position and thus becoming effective to consummate a printing operation, a performance depending upon the movement of its parallel bail bars 81 to an extent indicated in dotted outlines in Fig. 6. Instead, these bail bars are held as indicated in Fig. 4 opposing the effect of the power spring 82. Restoration of the assembly 79 moving it to its clockwise extreme position is the function performed by a cam carried upon shaft 16 but independently driven thereat after the manner explained in the above-referred to patent.

As best indicated in Figs. 2 and 9, a roller 83 is disposed between the afore-mentioned bail blades 81 of the bell crank assembly 79 and is pivotally carried upon a stud 84 which forms part of an integral assembly, including among other things, a pull bar actuating bail 85, Fig. 2, constrained to parallel horizontal movement by a pair of opposite guide rollers 86 within the guide frames 87.

The motion imparted to roller 83 is in turn communicated to the pull bar bail blade 85 thrusting the latter member first leftwardly, Figs. 2 and 9, then restoring it rightwardly in sharp staccato motion. During its movement leftwardly, its acute angled shoulder engages any one of the shoulders 88 of a selectable pull bar conditioned by the disposition of the set of curved selector bars 25 and this causes an associated one of the type bars 26 to be thrust against the printing platen 149 after the manner of the dotted outlined position 90 in Fig. 9. The prevention, as by the coaction of print suppression member 77 with shoulder 76, of the full reciprocal motion of the bell crank assembly 79 prevents the corresponding movement of pull bar bail 85, and consequently the printing operation which may be otherwise selectively prepared on account of the code combination signal affecting the conventional five selector vanes 17 and the consequent code setting of the curved code bars or segments 25 is suppressed.

As a result, the receipt of a code signal, when the sixth selecting vane 17a is disposed in its marking position (shown in Fig. 2), has no effect on the printing mechanism in accordance with the mechanical embodiment featured in Figs. 1 to 6.

When any one of the several tapes 31 is selected, therefore, the printing carriage 22 will be moved rightwardly, Fig. 1, until the printing locus; that is, the point at which the type pallets 26 strike the ribbon 89, will coincide with the left-hand column of one of the printing tapes 31 and will thereafter in accordance with the conventional responses of printing telegraph machines move one step distance to the right in contemplation of the printing operation of a succeeding character. Since the proposed embodiment contemplates the printing of numerals or upper case characters solely, it will be understood that the information typed upon any one of the paper ribbons 31 will consist almost entirely of numeral or fraction characters. This practice is designed to accommodate the requirement of stock quotation reporting where each one of the tapes 31 is allocated to a particular stock and, upon the

selection of such a tape (that is, the movement of the carriage to the vertical column corresponding thereto), results in a preliminary preparation contemplating the printing of the price which may be performed by means of numeral and fraction characters and does not require the printing of alphabetical characters.

In the preferred embodiment, Figs. 1 to 6, the platen consists of a series of cylindrical backing rolls 91 arranged on a common axis, each roll 91 in alignment with a corresponding magazine trough 92, by which term is meant one of the semi-circular faces divided off by the partitions 93 and within which there may be reposed a supply roll 94 of ribbon material resting upon one or more of the longitudinal supporting rails 95.

The ribbon or material as it is stripped from its supply roll 94 is directed over a curved transverse guide member 96 so as to make certain of clearing a horizontal transverse bail 97 utilized in effecting the line feed operation as will presently be described. The ribbon after being directed around its individual platen roller 91 then extends upwardly and over a feed roller 98 against whose periphery it is held by means of the bell crank supported tensioning roller 99.

From the periphery of feed roll 98, ribbon 31 extends to a spring loaded take-up roll 101 carried by an individual take-up reel 14 and powered by an involute spring 102 which may be manually wound when required so as to impart a clockwise torque to the reel 14 when the adjacent disc 103 to which the internal end of the spring 102 is fastened and which in turn is latched in spring loaded position by means of a latch pawl 104.

It is proposed that the power capacity of each spring 102 may be sufficient to take care of the maximum requirements of the most active stock which may be represented by one of the columns and one of the paper ribbons 31. As a consequence, continuous pulling tension is applied to each one of the ribbons 31 and transmitted on through to its point of engagement with the detented feed roll 98, Fig. 2, each member of which is individually actuatable when its feed pawl 105 is reciprocated in a vertical direction as permitted by the longitudinal openings 106 held by transverse supporting rods 107. The uppermost extremities of the several pawls 105 are toothed as at 108, and thereat engage the ratchet wheel teeth of individual wheels 109 rotating the latter members in a clockwise direction upon upward movement of said pawls and overcoming the effects of detenting pawls 111 which are spring urged to maintain their set position following each pawl operation. Springs 112 assist in maintaining the operational engagement between pawls 105 and their ratchet wheels 109 while a guide comb 113 extending in a horizontal direction affords lateral support to said pawls 105.

Feed pawls 105 are normally retained in their down position under the influence of individual springs 114 which engage sidewardly extending lugs integral with the pawls 105 and are suitably secured in a stationary part of the framework. The lowermost extremities of the pawls 105 are square shouldered and beneath each one there is disposed an individual striker arm 115 of a lever whose opposite arm 116 extends beneath the transverse bail 97, previously described. Since lever 115-116 is pivotally carried at 117, it travels with the carriage 22 and hence is brought into alignment with any one of the pawls 105 when the printing locus of the carriage is in alignment with its associated tape 31, a sidewardly extend-

ing ledge 118 integral with the striker arm 115 being of sufficient width to align with the lower extremity of pawl 105 during all of its conditions of alignment with any one of the particular stock tapes 31.

Ball 97 is pivotally supported at opposite anchor points 119 and is actuated by means of the link 121 extending from its pivotal connection 122 to an ear 123 of a bell crank 124 pivoted at 125. 10 The depending arm of bell crank 124 is pivotally connected as at 126 to a line feed plunger rod 127 provided with a shoulder at 128 engageable by the transverse common operating bail blade 129. Bail blade 129 is carried upon an arm 131 pivoted on shaft 57 and actuated by an arm integral with arm 131 and powered by a cam integral with shaft 16. Accordingly, during the continuous rotation of shaft 116 bail arms 131 and operating bail blade 129 continue in reciprocable movement engaging and actuating any selectable push bars, such as the line feed bar 127, that is moved upwardly disposing its shoulder 128 in the path of the blade 129.

The manner of operating bail blade 129 and the cam which performs its function are not illustrated in detail since this mechanism pertains to well-known construction shown in the above referred to U. S. patent. The selective disposition of any one of the push bars, such as line feed bar 127, is under the control of an auxiliary member 132 pivoted upon the afore-described transverse shaft 21 and provided with a vertical coded section such as that designated 18 in Fig. 2. Accordingly, its selective movement in a counterclockwise direction about pivot 21 under the influence of an individual spring such as the spring 12 causes the lifting of its portion 132 and consequent disposition of bar 127 in the path of blade 129.

40 Following a selective actuation, that is, operated rightwardly by the blade 129 of member 127, bell crank 124 is rocked counterclockwise about its pivot 125 pulling link 121 downwardly and striking the common bail 97 against the tail arm 116 of lever 115-116 which performs, 45 through feed pawl 105, the afore-described line feed operation and consequent advancement of the associated tape 31 then being imprinted.

50

Modification

For purposes other than recording stock quotations there may be required facilities for printing lower case characters, as well as numerals or other characters occurring in the shift position 55 and for this purpose there is proposed herewith a modified structure featured in Figs. 9 to 11. In describing this embodiment, only those portions of the apparatus which are structurally different from the disclosure in the foregoing description 60 will be mentioned, it being understood that the other portions may be essentially the same in construction.

Instead of the selectable member 19, the modified adaptation utilizes a corresponding element 65 designated 141, of slightly different contour and being undercut in the proximity of the sixth vane 17a so as to be unaffected thereby and being provided with a sidewardly and upwardly extending 70 projection at 142 which registers in horizontal alignment with a bar 143 that extends the full width of travel of the carriage and is provided with a single notch designed to register with the sidewardly extending projection 142 when the 75 printing carriage 22 is brought into carriage re-

turned or beginning of line position, in alignment with the first tape 31.

By providing that the notch in bar 143 be located in a particular position, it is thus rendered possible for member 141 to assume its selected condition, upon being freed by the downward movement of cam bar 73, under but one condition in terms of the relative position of printing carriage 22. Since this is so it follows that the selecting code combination which may be made to effect the arrestment of printing carriage 22 in any of several positions as explained in the foregoing preferred embodiment may also be utilized for performing print hammer operation and may accordingly serve the dual purpose of arresting the carriage 22 and thereafter of causing the printing of certain alphabetical characters on any one of the particular tapes 31.

The sidewardly and upwardly extending lug 142 which is formed as an appendage to the vertical arm 75 of function lever 141 prevents this lever, under certain conditions of operation, from rocking counterclockwise about pivot 21. The shoulder 144, which corresponds in location and performance to the aforescribed blocking shoulder 76, is adapted to become interposed beneath the bail portion 77 just as in the preferred embodiment. A differentiation between the two systems resides in the manner of utilizing the present improvement following each selection and printing. Since each column position may be selectively determined only from the starting or beginning of line position, it follows that concluding the printing operations in each selected column, it is necessary to send a carriage return signal which in the manner of conventional operation serves to move the carriage 22 leftwardly (Fig. 1) to its extreme leftward position whereat the notch in bar 143 is again aligned to receive the projection 142. Of course, if it is advisable to provide several notches in bar 143 consecutive selection from preceding arrestment conditions may accordingly be attained.

In this way, the printing of a character is prevented when the type carriage is in its starting or beginning of line position. Thereafter, however, when the type carriage moves away from the position in which selectable element 141 may move inwardly as through the admission of its lug 142 in the notch of bar 143, then shoulder 144 will not advance far enough to intercept the function bail portion 77. The counterclockwise movement of member 141 notwithstanding the obstruction effect of its blocking shoulder 144 on bail member 77 is sufficient nevertheless, as shown in Fig. 4, to permit pawl 42 thereof, traveling leftwardly about shaft 21 as a center, to engage a succeeding tooth of parallelly moving bar 46, and upon the return movement of member 141 the rightward motion of pawl 42 causes said bar 46 to engage and operate contact pair 51 and also, through member 53, to rock the stop lever 56 out of its position wherein it blocks the escape disc 62. Thereafter, the responses continue as in the preferred embodiment, the operation of the several elements being otherwise substantially identical with that of the foregoing description.

The tape upon which the printing is done is obtained from a plurality of supply rolls 94, Fig. 9, which lie in partitioned troughs 92 from which the web is withdrawn and directed over a guide rod 145. This is to give the web 31 sufficient clearance to avoid the path of an operating bail 146 (Fig. 9) whose performance will be described later. The web 31 after passing over guide rod

145 is directed downwardly and over an individual feed roller 147 against whose periphery it is held by means of a spring loaded pressure roller 148. Then, the web 31 is directed upwardly over a printing anvil 149, and thence over uppermost guide roll 151 where the tape is again tensioned by an auxiliary roll 152 to be wound up on a spring loaded take-up roll 14, just as in the case of the preferred embodiment discussed above.

As may be better observed from the enlarged detail view of Fig. 11 the feed roller 147 is preferably mounted on a shaft common with an escape pallet wheel 153 whose teeth are engaged on the one hand by a principal pallet pawl 154 (Fig. 9) augmented by an auxiliary pallet pawl 155. The tooth of principal pawl 154 normally engages one of the teeth of wheel 153 with the tooth of auxiliary pawl 155 withdrawn but poised in readiness to enter when principal pawl 154 is rocked clockwise about its supporting pivot 153 and is cammed by pin 157 which rides in a longitudinal slot 158 on the trailing arm of said pawl 155. Upon the return movement of the principal pawl 154 a reverse motion is imparted by the pin 157 engaging in said slot 158 causing the tooth of auxiliary pawl 155 to be withdrawn and the tooth of principal pawl 154 to be reinstated. During the interim, an escape movement of an angular distance corresponding to one of the teeth of wheel 153 is thereby effected. Because of the torque imparted by the spring-loaded take-up reel 14, the tape 31 is continuously urged in wind-up direction so that when the afore-described tooth escapement obtains, impetus to the tape 31 permits the line feed operation to be thereby effected.

Integrally formed with pawl 154 is a downwardly extending arm 159 which lies in the path of a transverse bail 146 pivoted at its extremities 161 in supporting arms 162 carried by the printing carriage 22 described above. Since the carriage 22 is movable transversely throughout the distance afforded by the guide and supporting rails 68 and 69, it follows that the several tapes 31 after leaving their supply rolls 94 must be held high enough to clear the path described by the uppermost extremity of striker bail 146 as it, too, travels this distance. Bail 146 is spring urged in counterclockwise direction about its pivot 161 but is prevented from moving into engagement with any of the arms 159, with which it happens to be in alignment, by the intervention of a horizontal bar 163 integrally associated with a bell crank 164, another arm of which is pivotally articulated as at 165 to the line feed actuating link 166. In the present embodiment, link 166 is connected at its lower extremity to the bell crank 167 pivoted at 168 and which is rotatable in a counterclockwise direction about its pivot upon being actuated by the selectable plunger 127 as described in the preferred embodiment above.

A selection of member 132 and the consequent selective displacement of bar 127 is a response of the principal telegraph apparatus to a conventional type of line feed signal whereupon the shoulder 128 is raised sufficiently to come into the path of common operating bail 129 carried by arm 131. In consequence, bell crank 167 is rotated counterclockwise, link 166 is pulled downwardly, bell crank 164 is rotated clockwise and bail 146 is then permitted to respond the urge of its spring 169 and shift arm 159 leftwardly, as viewed in Figs. 9 and 11, thereby producing the escapement movement of pawls 154 and 155 as already described.

A pair of selectable elements resembling in performance the element 132 acts upon a corresponding pair of bars opposing each other on the opposite ends of a lever 171 pivoted at 172 and designed to impart clockwise and counterclockwise motion to a bell crank lever 173 which is pivoted at 174. These two selections are termed shift and unshift and their object is to effect a disposition of the typing platen so as to register with the upper and lower case characters on the type pallet 26 when they are in printing position as designated in dotted outlines at 89, Figs. 9 and 11.

The manner in which its motion is transmitted to the bell crank 173 is fully explained in the above-mentioned patent, and for the present purpose it will suffice to feature in the drawing that portion only of the mechanism subsequent to the bell crank 173 and including link 176, in Fig. 9. The case shift lever 177 is illustrated in Fig. 9 in letters or unshift position and upon the rotation of bell crank 173 in a clockwise direction, link 176 will be pulled downwardly and lever 177 will be rotated clockwise about pivot 156 causing a transverse bail 178 to be lifted.

As a consequence of the lifting of bar 178 from the letters to the figures shift position, which is its movement from solid to the dotted outline position in Fig. 11, a single lever 179, pivoted at 181 in a suitable place on the printing carriage, is rocked counterclockwise in opposition to its return spring 182, and by so moving, a sidewardly extending ledge 183 thereof engages and raises one of the side plates 184 which support the ends of the shaft 185. These side plates 184 are pivoted on shaft 156. This movement causes the side plates 184 to shift from their solid outline to their dotted outline position, Fig. 11, causing the roller 147 to be correspondingly raised and with it platen 149 which is moved to the dotted outline position in registration with the figure characters of the type pallets when disposed in the printing position 90.

The limits of motion in executing the case shift movement may be regulated by means of the adjustment screws 191 and 192 (Fig. 11) which limit the distance of movement of a sidewardly extending stop lug 193. When the printing apparatus is employed in the figure shift position it is contemplated to restore it to the letter shift position before a subsequent tabulation operation is undertaken.

While the present invention has been explained and described in connection with specific embodiments, it will be understood that numerous modifications and variations may be made without departing from the spirit or scope thereof. It is accordingly not intended to be limited by the particular illustrations in the accompanying drawings nor by the detailed descriptions employed in the foregoing specification except as limitations are indicated in the hereunto appended claims.

The invention claimed is:

1. In a permutation code signal selecting mechanism, a set of coded selectors, a selectively positionable device adapted to be moved longitudinally of said selectors and to traverse said selectors, means carried by said device responsive to the coded notchings in said selectors, means for limiting the movement of said device to one character space, means for rendering said limiting means ineffectively, thereby to enable continuous movement of said device through a plurality of character spaces at a time, and apparatus for re-

storing the effectiveness of said limiting means upon encounter with a distribution of notchings corresponding to said device.

2. In a permutation code selecting apparatus, 5 a series of coded selector bars each having variously distributed V-notched coding, a device traversing said bars and movable longitudinally thereof having probing engagement with said bars in accordance with the notchings thereon, 10 means for limiting the movement of said device to one character space, means for rendering said limiting means ineffective, thereby to enable continuous movement of said elements through a plurality of character spaces at a time and means for restoring the effectiveness of said limiting means upon encounter with an arrangement of notchings corresponding predeterminedly to the disposition of said device.

3. In a permutation code selecting mechanism, 20 a series of code bars each having variously distributed code notchings on corresponding edges thereof and arranged in various alignment transversely, a device for selecting a linear position relative to said series of bars comprising a plurality of code notch sensing elements one associated with each of said bars and collectively carried by said device, and means for effecting a selective response upon encountering notchings in said bars in correspondence with the disposition of said probing elements of said device.

4. In a printing telegraph apparatus, a type basket comprising a segmental arrangement of type elements each pivoted so as to strike against a common printing locus, an alignment of printing platens each associated with a separate supply of print marking receiving material, telegraphically controlled means for advancing said type basket to address each one of said platens selectively, and line feed mechanism for rotating 35 an addressed platen and thereby advancing said material exclusively when said type basket is in registration therewith.

5. In a telegraph printing system, a plurality of platens arranged on a common horizontal axis, 45 tape feed means associated with each one of said platens including a tensioned take-up roll for said platens, a pallet and escape reel mechanism associated with each one of said platens, a movable carriage, telegraphically controlled means for advancing said carriage to address each one of said platens selectively and means responsive to a line feed signal for selectively actuating said pallet and escapement mechanisms when said carriage is in registration therewith to permit the advancement of the tape thereof.

6. A selecting apparatus comprising a series of notched bars parallelly arranged in which said notches are distributed variously in accordance with a plurality of transverse code patterns, a selectable member having probing elements each shiftable to afford predetermined code setting adjustment, and means for probing said notchings on said bars during linear movement of said member in accordance with the predetermined setting of said elements thereon.

7. In a page printing telegraph apparatus, a shiftable type carriage, a trackway having notch and lug code markings arranged parallel to the movement of said carriage, and means carried by said carriage for traversing said trackway including selectable elements controlled by the code markings in said trackway for effecting the arrestment of said carriage accordingly.

8. In a page printing telegraph apparatus, a horizontally shiftable printing carriage, a rotary

collar mechanism for moving said carriage in a direction of tabulation, a series of elements, each having variously distributed code notchings on corresponding edges thereof along the course of travel of said carriage, said notchings arranged in various alignments transversely, probing means carried by said carriage, and means under the control of said probing means upon attainment of predetermined alignments of said code notchings for arresting the communication of power from said rotary source.

9. A case shift apparatus for multiple platen printing mechanisms comprising a plurality of platens arranged in a linear alignment, a shiftable printing mechanism movable parallelly to said linear alignment for printing upon said platens selectively, a case shift mechanism for raising and lowering said platens in accordance with predetermined selecting signals therefor, and a case shift member communicatingly carried by said printing mechanism for imparting the case shift movement of said apparatus to predetermined ones of said platens in accordance with the alignment of said carriage.

10. In a printing telegraph apparatus, a plurality of coded selecting elements, a shiftable printing carriage, a selector predeterminedly responsive to the arrangement of said selecting elements for moving said carriage in tabular shift manner, and a device for preventing the selection of said selector in any other than predetermined position of said carriage.

11. In a printing telegraph apparatus, a shiftable carriage, horizontal guide means for supporting said carriage in its transverse movement of shifting, code combination conditionable means extending parallelly to the path of travel of said carriage, a selectable member responsive to said means for moving said carriage from a zero position to predetermined ones of a plurality of tabulation positions, and a device for preventing the selective response of said selector means in any but said zero position of said shiftable carriage.

12. In a printing telegraph machine, a shiftable carriage, a permutation code selecting mechanism supported by said carriage, means parallel to the path of travel of said carriage having multiple code combination characteristics, and code characteristic sensing apparatus conditionable by said selecting mechanism to accord selectively with said multiple code combination characteristics.

13. In a shiftable platen mechanism for typing machines, a plurality of platens arranged in alignment, a printing carriage shiftable parallelly to said alignment, a lever for shifting said platens between alternative case positions, and an interponent carried by said carriage constituting a linkage between said lever and any one of said plurality of platens opposite which said carriage is disposed.

14. In a recorder, a plurality of stationary paper carriers, a single type carriage movable with respect to said carriers to form character spaces, permutation code mechanism mounted on said carriage including longitudinally adjustable code members, means to operate said code mechanism permutably according to the record to be made, and means to select the paper carrier with which the type carriage is to cooperate to make the record.

15. In a recorder, a stationary supporting framework, a plurality of paper carriers mounted in said framework, a type carriage movable with respect to said paper carriers, and means to

select the paper carrier with which the type carriage is to cooperate to make a record.

16. In a recorder, a stationary supporting framework, a plurality of paper carriers mounted in said framework, a type carriage movable with respect to said paper carriers, a printing ball in said framework, slideable connecting means between said carriage and said ball to effect recording operations, and means to select the paper carrier with which the type carriage is to effect said recording operations.

17. In a recorder, a stationary supporting framework, a plurality of carriers of record-receiving material mounted in said framework, recording means movable with respect to said carriers, and means to select the carrier with which the recording means is to cooperate to make a record.

18. In a recorder, a stationary supporting framework, a plurality of carriers of record-receiving material mounted in said framework, recording means movable with respect to said carriers, a ball in said framework, slideable connecting means between said recording means and said ball to effect recording operations, and means to select the carrier with which the recording means is to effect recording operations.

19. In a telegraph printer, a plurality of stationary paper carriers, a traveling type carriage, means for effecting the normal spacing movement of said carriage, selecting mechanism, further means operable under the control of said selecting mechanism to render said spacing means ineffective and to facilitate the continuous movement of said type carriage, a series of members notched in accordance with a predetermined coded pattern, and probing means carried by said type carriage and operable with said notched members to control the movement of said carriage to a selected one of said paper carriers.

20. In a recorder, a plurality of stationary carriers of record-receiving material, recording means, means for effecting the normal spacing movement of said recording means, selecting mechanism, further means operable under the control of said selecting mechanism to render said spacing means ineffective and to facilitate the continuous movement of said recording means, a series of members notched in accordance with a predetermined coded pattern, and probing means carried by said type carriage and operable with said notched members to control the movement of said carriage to a selected one of said carriers.

21. In a telegraph printer, a plurality of printing platens, a single traveling type carriage operable therewith, a case shift mechanism individual to each platen, means to select the platen with which the type carriage is to cooperate to make a record, and means associated with the type carriage to operate the case shift mechanism individual to the selected platen.

22. In a recorder, a plurality of platens, a single recording means cooperable therewith, a case shift means individual to each platen, means to select the platen with which the recording means is to cooperate to make a record, and means associated with the recording means to operate the case shift means individual to the selected platen.

23. In a recorder, a stationary supporting framework, a plurality of carriers of record-receiving material mounted in said framework, recording means movable with respect to said carriers, function controlling means carried by said recording means, means to select the carrier with

which the recording means is to cooperate to make a record, and means to render said function controlling means effective at the selected carrier.

24. In a telegraph printing system, transmitting means, a receiving means comprising recording instrumentalities, a plurality of carriers of record-receiving material, means for effecting the normal spacing movement of said receiving means, selecting mechanism, further means op-

erable under the control of said selecting mechanism to render said spacing means ineffective and to facilitate the continuous movement of said receiving means to a selected one of said carriers, and means controlled by said further means to render said transmitting means ineffective during the continuous movement of said receiving means.

LOUIS M. POTTS.
